UNITED STATES PATENT OFFICE.

JAMES REAGAN, OF PHILADELPHIA, PENNSYLVANIA.

GRATE.

1,112,383.

Specification of Letters Patent. Patented Sept. 29, 1914.

Application filed July 16, 1913. Serial No. 779,365.

To all whom it may concern:

Be it known that I, JAMES REAGAN, citizen of the United States, residing at Philadelphia, in the county of Philadelphia and State of Pennsylvania, have invented certain new and useful Improvements in Grates; and I do hereby declare the following to be a full, clear, and exact description of the invention, such as will enable others skilled in the art to which it appertains to make and use the same.

The invention relates to grates in general, but more particularly to furnace grates of the type commonly known as "rockable-bar" grates; and it consists in the peculiar construction and arrangement of the several parts and their combination, as will be hereinafter fully described in this specification and briefly stated in the claims.

One of the chief objects of the invention is to provide a chopper which can be readily detached from the rocking-bar and replaced without taking the grate apart or removing the rocking-bar.

Another and important feature of the invention is to provide ample space between the rocking bar and choppers for the passage of air through the grate and thence to the fire-chamber.

Still another object of the invention is to provide a simple and effective device for mechanically stoking the fire.

Heretofore it has been found necessary, in order to reline the furnace walls or make other repairs thereto to remove entirely the inner parts of the grate, leaving only the frame, so that the workmen may have free access to the parts to be relined or repaired. The present invention is designed to overcome this difficulty, as an entire row of choppers may be readily removed so as to provide ample space for the workmen engaged in making the repairs, without removing the rocking-bar or other parts of the grate.

Other objects of the invention, such as providing a spanner which does not require removal when a chopper is to be removed for any purpose, or a row of choppers is to be removed to make repairs, will become apparent upon a complete disclosure thereof.

In the drawings—Figure 1 is a perspective view of a grate showing my improvement applied thereto; Fig. 2, a central longitudinal section thereof; Fig. 3 a rear end

elevation; Fig. 4 a side elevation of one of the grate-bars removed, showing a row of choppers mounted thereon; Fig. 5 a perspective view of one of the choppers; Fig. 6, a modified form of chopper; Fig. 7 a perspective view of the grate showing the stoking device in action; Fig. 8, a perspective view of one of the stoker-castings; Fig. 9, a side view of one of the bridge-bars, and Fig. 10 a plan and a perspective view, respectively of one of the sections of the front head-block.

Referring to the several views, the numeral 1 indicates the frame of the grate; 2, 2' the front head and rear head-blocks, respectively, 3, 3', the bridge-bars. The head-blocks are made in detachable sections as shown in Fig. 1, each section comprising a flanged plate having an inwardly-extending lug, the plate and lug being provided with aligned apertures, as shown in Fig. 10, to receive a securing-pin, not shown; and the bridge-bars are provided with air-passages 3'' as shown in Fig. 9, and both the head-blocks and the bridge-bars are provided with clinker cutting edges.

Detachably mounted upon the square bars 4, between the head-block and the adjacent bridge-bar are two rows of choppers 5, each chopper being provided with clearance openings 6, clinker-crushing teeth 7, and an end cutting edge 8 which is adapted to contact with one of the cutting edges of either the head or tail-blocks and the bridge-bars. The lower portion of each chopper is bifurcated to provide attaching legs 9 for straddling the rocking-bar 4, and be detachably secured thereon by a key or wedge 10 fitting in recess 11 made in opposite faces of the legs, said key being prevented from longitudinal-movement by lugs 12, 12, which set against one side of the attaching-legs and by a cotter or lynch-pin 13. In fitting the grate with the choppers it is customary to employ wide choppers in the center part of the grate, and narrow choppers at each side thereof, and on the wide choppers I prefer to duplicate the attaching-legs 9 as shown in Fig. 6, or instead of the duplicate attaching-legs 9, I may provide the chopper with an attaching-leg 9 and with a bifurcated leg 14 to insure additional stability for such chopper, as shown in Fig. 5, or I may employ two such bifurcated arms 14, one each side of the attaching-legs 9. The

100
105
110

legs 14 besides insuring greater stability for the chopper also serve to take part of the strain off of the legs 9.

The numerals 15 and 16 indicate long and short spanners respectively, each being provided with a square hole to adapt it to be slid on the rocking-bar to the proper or desired position before the choppers are placed thereon, as shown in Fig. 4, the spanners 15 being connected with shaking-lever 18 by links or rods 19, and spanners 16, connected with spanners 15 by tie-bars 20.

It will be noted that the spanners, both long and short, may be placed on the rocking-bars either between the choppers, or between the attaching-legs and bifurcated legs as may be found convenient to bring them in direct line with the shaking-devices. By providing spanners which do not require to be removed in making repairs or changing choppers, a great advantage over the spanners which require removal to permit changes and repairs to be made is obtained, as they are always more in proper position to be operated by the mechanism which operates the choppers, besides there is more or less danger in replacing choppers which require removal in wrong position by inexperienced workmen after changes in burned parts have been made.

The rocking-bars are provided at each end with a cylindrical journal block 21, so as to adapt them to be journaled in bearings 22 made in the respective sides of the frame.

The numeral 23 indicates a small drop grate extending downwardly from the dead-plate 24 to the surface or top of the grate proper. By the employment of the drop-grate, the grate proper may be lowered without necessitating the removal of the dead-plate at the front of the boiler, which is a great advantage, as by lowering the grate proper forty or fifty inches from the bottom of the boiler the oxidation of the smoke is facilitated and combustion promoted, air admitted to the grate keeps the fire off the dead-plate, and the condition of the fire at the bridge-wall can be seen from the front.

By using a square rocking-bar, preferably one and one-half inches square, and mounting thereon my peculiarly constructed choppers an air space is provided between each row of choppers and their bar, which preserves the rocking-bars from warping and burning out, and delivers the air equally to the grate.

The stoking-device is composed of a number of stoker-castings 25 arranged between the choppers, as shown in Figs. 1, 2 and 7. Each stoker-casting is provided at one end with a hole 26 in which is fitted a spool 26' to serve as a journal-bearing mounted on one of the square rockable bars 4, so that

the stoker-castings may be rocked independently of the choppers. The opposite end of each stoker-casting is provided with a curved slot 27, open at its lower end, in which the adjacent rockable-bar 4 is received, so as to permit the lifting-action of the stoker-casting. Each stoker-casting is also provided with a depending arm 28 to which operating rods or links 29 are attached, each longitudinal row of stoker-castings being connected together, one row being shown in Fig. 7.

When the stoker-device is in action, as shown in Fig. 7, the fire is thrown back and when it is not in action it is a part of the grate, supporting the fire while being cleaned by the choppers, and is provided with air-cooling spaces or openings.

By making the front head-block in detachable sections, any section may be easily and readily removed when burnt out, and replaced by a new one. In fact any piece or part of the grate surface may be removed, and replaced by a new one without disturbing the frame, or the pulling-power or connections that tie the grate together, which is an important advantage over the grates now in use.

Having thus fully described my invention, what I claim is:

1. A furnace grate, having in combination a square rocking-bar, a plurality of choppers, each having a plurality of pairs of legs adapted to straddle the rocking-bar and provide air-spaces between the choppers and said bar, one pair of said legs coacting with keying means for detachably-holding the choppers on the bar against vertical and lateral play, but allowing said choppers to be removed in a vertical direction without a lateral displacement.

2. A furnace grate, having in combination a square rocking-bar, a plurality of choppers, each having a plurality of pairs of legs adapted to straddle the rocking-bar and provide air-spaces between the choppers and said bar, one pair of said legs coacting with keying means for detachably-holding the choppers on the bar against vertical and lateral play, but allowing said choppers to be removed in a vertical direction without a vertical displacement, spanners arranged on the rocking-bar, between the pairs of legs, and means for rocking the spanners and thereby the choppers.

3. A furnace grate, having in combination a square rocking-bar, a plurality of choppers, each having a plurality of pairs of legs adapted to straddle the rocking-bar and provide air-spaces between the choppers and said bar, one pair of said legs coacting with keying means for detachably-holding the choppers on the bar against vertical and lateral play, but allowing said choppers to be removed in a vertical direction without a lat-

eral displacement, bridge-bars having horizontal air-spaces therethrough, and independent means for rocking the choppers.

4. A furnace grate, having in combination a square rocking-bar, a plurality of choppers, each having a plurality of pairs of legs adapted to straddle the rocking-bar and provide air-spaces between the choppers and said bar, one pair of said legs coacting with keying means for detachably-holding the choppers on the bar against vertical and lateral play, but allowing said choppers to be removed in a vertical direction without lateral displacement, independent means for 10 rocking the choppers, stoker-castings journaled on the bar, between the choppers, and means for elevating the stoker-castings so as to raise and hold the fire-bed in suspension while the choppers are being rocked.

20 5. A furnace grate, having in combination a square rocking-bar, a plurality of choppers, each having a plurality of pairs of legs adapted to straddle the rocking-bar and provide air-spaces between the choppers and said bar, one pair of said legs coacting with keying means for detachably-holding the choppers on the bar against vertical and lateral play, but allowing said choppers to be removed in a vertical direction without 25 lateral displacement, independent means for 30 a lateral displacement, independent means

for rocking the choppers, head and tail-blocks comprising a number of sections, each adapted to be attached to the respective head and tail-bars of the grate frame by securing pins, and bridge-bars provided with oppositely-disposed cutting edges and with air-spaces therethrough. 35

6. A furnace grate, having in combination a square rocking-bar, a plurality of choppers, each having a plurality of pairs of legs adapted to straddle the rocking-bar and provide air-spaces between the choppers and said bar, one pair of said legs coacting with keying means for detachably-holding the choppers on the bar against vertical and lateral play, but allowing said choppers to be removed in a vertical direction without a lateral displacement, spanners arranged on the rocking-bar, between the pairs of legs, means for rocking the spanners and thereby the choppers, stoker-castings journaled on said bar, between the choppers, and means for elevating the stoker-castings. 40 45 50

In testimony whereof I affix my signature, 55
in the presence of two witnesses.
